(57) **CLAIM**

I claim the ornamental design for a pump for a bottle of facial lotion, as shown and described.

DESCRIPTION

FIG. 1 is an upper perspective view of the pump for a bottle of facial lotion showing my design.

FIG. 2 is a back view thereof;

FIG. 3 is a top view thereof;

FIG. 4 is a side view thereof;

FIG. 5 is a front view thereof; and,

FIG. 6 is an opposite side view thereof.
